CLAIM

The ornamental design of a three-pronged connector clip, as shown and described.

DESCRIPTION

FIG. 1 is a perspective view of the invention.

FIG. 2 is a front elevational view of the invention.

FIG. 3 is a left side elevational view of the invention.

FIG. 4 is a top plan view of the invention.

FIG. 5 is a rear elevational view of the invention; and,

FIG. 6 is a bottom plan view of the invention.

The left and right sides of the invention are mirror images of each other, and thus only the left side views are shown in the drawings.
